UNITED STATES PATENT OFFICE.

FRITZ STAHLI, OF WINTERTHUR, SWITZERLAND.

LUBRICATING-PUMP.

No. 909,471.

Specification of Letters Patent.

Patented Jan. 12, 1909.

Application filed April 16, 1908. Serial No. 427,393.

To all whom it may concern:

Be it known that I, FRITZ STAHLI, a citizen of the Republic of Switzerland, residing at Winterthur, Switzerland, have invented certain new and useful Improvements in Lubricating-Pumps; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to lubricating pumps having pressure and governing pistons. In lubricating pumps of this kind the pressure and governing pistons have separate piston rods which are set in motion by means of eccentrics operated from some moving part of the engine or machine to be lubricated. Where the lubricating pump is employed on steam cylinders, a vacuum can draw the piston or working pressure may lift it, which may cause an irregular feed of oil to the cylinder, and a penetration of steam into the oil container, or the same may be sucked empty by means of the vacuum. Differential pistons have been provided in one cylinder but both acted as pressure pistons.

The objects of the present invention are to provide a governing and a pressure piston arranged on a single piston rod which is positively movable; means by which the oil to be forwarded at each stroke is measured; means to adjust the piston rod to alter the quantity forwarded; and means by which direct communication between the oil container and the space lying beneath the governing piston is avoided in all positions of the governing piston.

In the accompanying drawings, Figure 1 is a vertical section of a pump embodying the features of my invention. Fig. 2 a plan view partially in section. Figs. 3 and 4 are detail views illustrating the working positions of the pistons. Fig. 5 is an enlarged detail vertical section of one form of construction of the piston and Fig. 6 is a similar view of a modified form of construction of piston.

Referring to the drawings 1 designates the oil container, 2 an eccentric which is set in rotation from any movable part of the machine to be lubricated, 3 a yoke formed in two parts surrounding the eccentric and connected with a guide rod 4. On each half of

the yoke are formed lugs 5 and 6 said halves being held together by screws 7. The lugs 5 and 6 have lateral recesses 8, Fig. 2, for the lateral insertion of screw bolts 9. These screw bolts 9 are held fast on the upper lugs 5 by means of nuts 10 and 11. The nuts 11 being mounted in recesses 12 suitably shaped to their periphery prevent the screw bolts from emerging laterally through the recesses 8. On the lower end of each screw bolt 9 is formed a loop 13 in which the head 14 of a piston rod 15 rests. The piston rods are mounted in cylinders 16 and carry governing pistons 17 and pressure pistons 18. A portion of the cylinder is contracted at 19 to substantially the diameter of the governing piston forming a measuring chamber 31. The pressure piston 18 has, as a stuffing box, a spiral spring 20 the coils of which are somewhat inclined to the axis and of rectangular section.

The governing piston is hollow and in the form of construction shown in Fig. 5, is secured at its bottom by means of screw threads 22' formed on a prolonged portion 23' of a reduced end 23 of the piston rod 15, by which means an annular recess 30' is formed. In the form of construction shown in Fig. 6 the prolonged portion 23' is omitted and the governing piston is secured at its top to threads 22 formed on the reduced portion 23 forming a chamber 30. The cylinder 16 has oil admission apertures 24 and the governing piston 17 is closed at the bottom and has oil admission apertures 25 and oil outlet apertures 26.

27 designates the pipe leading to the machine to be lubricated, for instance to the cylinders of a locomotive, in which pipe a non-return valve may be inserted, but which is not absolutely necessary.

The operation of the lubricating pump is as follows: When the pistons 17 and 18 are in the position shown in Fig. 1, oil flows from the oil container 1 through the openings 24 into and fills the chambers 31. Now if the piston rod descends as shown in Fig. 3 the openings 24 are closed and the oil contained in the chamber 31 is forced through the openings 25 into chamber 30 and out through the openings 26 under the pistons 17 into the pipe 27. The governing piston thus exerts no pressure on the oil. Now if the piston again rises from the lowest position Fig. 4, the openings 24 remain closed so long as the openings 26 are open. During this operation

it is therefore not possible for steam to flow into the oil container 1 or the latter to be drawn empty by the vacuum in the cylinder of the locomotive, if, for instance, a non-return valve provided in the pipe 27 should not close securely, or if there be no non-return valve provided in said pipe. The regulation of the quantity of oil forwarded and the alteration of the size of the space 31 is effected by the enlargement and diminution of the distance x of the loop 13 from the flange 6 by the adjustment of the screw bolt 9. The positive connection of the piston rod 15 with the eccentric 2 however remains constant, so that the piston is prevented from being influenced by the working pressure or vacuum, and thereby an incorrect governing, as is frequently possible in the lubricating pumps with separate governing and pressure piston, is avoided.

The suspension of the piston rod 15 by the head 13 in the loop 14 is a flexible one, without producing a deadpoint and prevents the piston from sticking in the cylinder 16.

25 I claim:

1. In a lubricating pump, the combination of a container having a discharge aperture, a piston controlling the aperture having a hollow dispensing member of smaller diameter provided with inlet and discharge ports.

2. In a lubricating pump, a container, a cylinder having an oil inlet, a piston in the cylinder having a hollow reduced end portion closing the end of the cylinder, said reduced end provided with inlet and discharge openings.

3. In a lubricating pump, a container, a cylinder therein having an inlet port and a contracted end portion, an oil delivery conduit, a piston in the cylinder controlling the inlet port and having a hollow reduced end portion fitting into and closing said contracted portion and forming an annular recess above the latter, said reduced portion having an inlet port communicating with the annular chamber and having an outlet adapted to communicate with the delivery conduit.

4. In a lubricating pump, a container, a cylinder therein having an inlet port and a contracted end portion, an oil delivery conduit, a piston in the cylinder controlling the inlet port and having a hollow reduced end portion fitting into and closing said con-

tracted portion and forming an annular recess above the latter, said reduced portion having an inlet port communicating with the annular chamber and having an outlet adapted to communicate with the delivery conduit and means to regulate the size of the annular recess.

5. In a lubricating pump, the combination with a container, of a cylinder having an oil inlet, a piston in the cylinder having a hollow reduced end portion closing the end of the cylinder, said reduced portion provided with inlet and discharge openings, a reciprocable member, and means to flexibly connect the piston and reciprocable member.

6. A lubricating pump comprising a container, a cylinder mounted in the container having a discharge port therein, a conduit, a pressure piston reciprocably mounted in the cylinder adapted to open and close said port, and a hollow governing piston of smaller diameter than the pressure piston connected to the latter and having an inlet communicating with the cylinder and an outlet adapted to communicate with the conduit.

7. In a lubricating pump, the combination with a container and a conduit, of a cylinder mounted in the container having a discharge port, a pressure piston mounted in the cylinder adapted to control said port, a hollow governing piston of smaller diameter than the pressure piston carried by the latter and having an inlet communicating with the cylinder and an outlet below the inlet adapted to communicate with the conduit when the discharge port is closed.

8. In a lubricating pump, the combination with a container, of a cylinder having an oil inlet, a piston in the cylinder having a flange on one end and a perforated hollow reduced portion on the other end closing the cylinder, and forming an annular recess in the latter, an eccentric, a yoke surrounding the latter, a bolt adjustable in the yoke having an open loop on one end to receive the flange of the piston.

In testimony that I claim the foregoing as my invention, I have signed my name in presence of two subscribing witnesses.

FRITZ STÄHLLI.
